CLAIM

The ornamental design for a device cover, as shown and described.

DESCRIPTION

FIG. 1 is a front perspective view of a first embodiment of a device cover;

FIG. 2 is a bottom view thereof;

FIG. 3 is a top view thereof;

FIG. 4 is a left-side view thereof;

FIG. 5 is a right-side view thereof;

FIG. 6 is a front view thereof;

FIG. 7 is an enlarged view of the area marked 7 in FIG. 6;

FIG. 8 is a back view thereof;

FIG. 9 is a front perspective view of a second embodiment of a device cover;

FIG. 10 is a bottom view thereof;

FIG. 11 is a top view thereof;

FIG. 12 is a left-side view thereof;

FIG. 13 is a right-side view thereof;

FIG. 14 is a front view thereof;

FIG. 15 is an enlarged view of the area marked 15 in FIG. 14; and,

FIG. 16 is a back view thereof.

The dashed broken lines depict portions of the device cover that form no part of the claimed design. The dot-dashed broken lines represent boundaries of the claimed device cover and form no part of the claimed design.
